ABSTRACT

An electron gun of uni-potential type is disclosed, which includes a main electron lens system consisting of a front electron lens system formed of a third grid and a fourth grid and a rear electron lens system formed of the fourth grid and a fifth grid of which the electron lens action regions are separated from each other. In this case, the electron lens diameter of the front electron lens system is selected smaller than that of the rear electron lens system, and the aperture diameter of the fifth grid in the rear electron lens system is selected larger than that of the fourth grid, and may be nearly as large as the inner diameter of the tube in which it is placed for use.

ELECTRON GUN WITH LOW SPHERICAL ABERRATION

This is a continuation of application Ser. No. 469,290, filed 2/24/83 now abandoned.

BACKGROUND OF THE INVENTION

1. Field of the Invention

This invention relates generally to electron guns and particularly is directed to an electron gun of uni-potential type with low spherical aberration.

2. Description of the Prior Art

Because an electron gun of uni-potential type has good blooming characteristic in the high electric current range, it is utilized in such devices as color picture tubes or projector tubes. In general, the electron gun of uni-potential type comprises a cathode K, a first grid (control electrode) G₁, a second grid (acceleration electrode) G₂, a third grid (first anode electrode) G₃, a fourth grid (focusing electrode) G₄, and a fifth grid (second anode electrode) G₅ arranged in this order. In this electron gun, in order that an electron beam may impinge with a smaller spot diameter on a phosphor screen surface, it is important to reduce as much as possible the spherical aberration of an electron lens, particularly a main electron lens formed of the third grid G₃, the fourth grid G₄ and the fifth grid G₅. To this end it is required that an aperture diameter of each grid in the main electron lens system is made large. However, in order to make the grid aperture diameter large, it is necessary that the cathode ray tube envelope in which the electron gun is incorporated to have a neck portion of large inner diameter. However, the provision of a larger inner diameter of the neck portion lowers the deflection sensitivity of a deflection yoke.

On the other hand, as shown in FIG. 1, when the unipotential lens consists of a decelerating lens Lens 1 formed of the third and fourth grids G₃ and G₄, and an accelerating lens Lens 2 formed of the fourth and fifth grids G₄ and G₅, its electron lens action region can be separated, so that the aberration coefficient of the main electron lens system can be considered as being separated into the decelerating lens Lens 1 side and the accelerating lens Lens 2 side. Since the aberration coefficient is small in the decelerating lens and large in the accelerating lens, if the aberration amount of the accelerating lens is improved to have a further weaker lens action, the whole aberration amount of the uni-potential lens can be improved.

FIG. 2 shows an electron gun with low aberration coefficient we have previously proposed as a Japanese patent application No. 15581/1977 (no corresponding U.S. patent application), on the basis of the fact that the aforesaid aberration coefficient of the main electron lens system can be separated into the decelerating lens side and the accelerating lens side. This previously proposed electron gun comprises a cathode K, a first grid G₁, a second grid G₂, a third grid G₃, a fourth grid G₄ and a fifth grid G₅ arranged sequentially in which an anode voltage V_A is applied to the third and fifth grids G₃ and G₅ and a focusing voltage V_F is applied to the fourth grid G₄ permitting the third grid G₃ to constitute a main electron lens system of unipotential type. In this electron gun, an electron lens diameter D₁ of the front decelerating lens (Lens 1) forming the main electron lens system (namely, an aperture diameter of each opposing end of the third and fourth grids G₃ and G₄) is selected

smaller than an electron lens diameter D₂ of its rear accelerating lens (Lens 2) namely, an aperture diameter of each opposing end of the fourth and fifth grids G₄ and G₅) or to satisfy D₂>D₁, and the fourth grid G₄ is made to have a length l=(l₁+l₂) so as to be capable of separating the electron lens action region into those of the front and rear lenses Lens 1 and Lens 2 whereby the aberration coefficient of the main electron lens system can be made small. In the art, each of the grids G₁ to grid G₅ is held by a common insulation holding rod (so-called glass beads). Consequently, when the electron gun with the grids held together by the insulation holding rod is incorporated into the neck portion of the cathode ray tube envelope, the need for the space of the insulation holding rod restricts the diameter of an aperture of grid. When the electron gun is incorporated into the neck portion of, for example, 29 mm in inner diameter, the effective inner diameter of the grid is about 14 mm at best. In view of such aspect, we have previously proposed the electron gun shown in FIG. 2 capable of reducing the aberration coefficient by making the diameter of the decelerating lens (Lens 1) small.

OBJECTS AND SUMMARY OF THE INVENTION

Accordingly, an object of this invention is to provide an electron gun of unipotential type capable of removing the afore-said defects.

Another object of this invention is to provide an electron gun of uni-potential type capable of reducing as much as possible a spherical aberration of a main electron lens system electron gun of uni-potential type suitable for use with a color picture tube or a projector tube and so on.

In accordance with an aspect of the present invention, there is provided an electron gun comprising a main electron lens system which consists of a front electron lens system formed of a third grid and a fourth grid and a rear electron lens system formed of said fourth grid and a fifth grid of which the electron lens action regions are separated from each other, in which an electron lens diameter of said front electron lens system is selected smaller than that of said rear electron lens system, and an aperture diameter of said fifth grid in said rear electron lens system is selected larger than that of said fourth grid.

Other objects, features and advantages of the present invention will become apparent from the following description taken in conjunction with the accompanying drawings through which the like references designate the same elements and parts.

BRIEF DESCRIPTION OF THE DRAWINGS

FIG. 1 is a cross-sectional view of a main electron lens of an electron gun used to explain this invention;

FIG. 2 is a cross-sectional view illustrating an example of a conventional electron gun of unipotential type;

FIG. 3 is a cross-sectional view illustrating a fundamental example of an electron gun according to this invention;

FIGS. 4 and 5 are respectively cross-sectional views of main parts of the prior art electron guns;

FIG. 6 is a graph concerning a spherical aberration coefficient and a focal length of the electron gun according to this invention and the conventional electron gun;

FIG. 7 is a graph used to explain how an equation of aberration coefficient is searched for;

FIGS. 8 and 9 are a plan view and a cross-sectional view illustrating an embodiment of electron gun according to this invention;

FIG. 10 is a cross-sectional view of another embodiment of the electron gun according to this invention;

FIG. 11 is a graph showing a relation between a current amount and a diameter of a beam spot with respect to the electron gun of this invention and the conventional electron gun.

DESCRIPTION OF THE PREFERRED EMBODIMENTS

Hereinafter, an electron gun of unipotential type according to this invention will be described with reference to the attached drawings.

FIG. 3 shows a fundamental example of an electron gun of unipotential type according to this invention which comprises in turn a cathode K and a first grid G₁ to a fifth grid G₅. In this example, a high voltage of, for example, anode voltage V_A is applied to the third and fifth grids G₃ and G₅ and a focusing voltage V_F much lower than the anode voltage V_A is applied to the fourth grid G₄ permitting the third grid G₃ to the fifth grid G₅ to constitute a main electron lens system of unipotential type. Also in accordance with this invention, the third grid G₃ and the fourth grid G₄ constitute a front decelerating electron lens (Lens 1), while the fourth grid G₄ and the fifth grid G₅ constitute a rear accelerating electron lens (Lens 2). Particularly in accordance with the present invention, the fourth grid G₄ is made to have its length l so as to separate the electron lens action regions of the front electron lens (Lens 1) and the rear electron lens (Lens 2) the front electron lens (Lens 1) is constituted to have its electron lens diameter smaller than that of the rear electron lens (Lens 2), and the fifth grid G₅ in the rear electron lens (lens 2) is constituted to have the aperture diameter larger than that of the fourth grid G₄. In other words, the fourth grid G₄ has at its side facing the third grid G₃ an aperture diameter D₁ and at the other side facing the fifth grid G₅ an aperture diameter D₂ larger than D₁, and the fifth grid G₅ is constituted to have its aperture D₃ larger than the above aperture D₂. Above-mentioned relationship is represented by an inequality D₁ < D₂ < D₃. Furthermore, in order to separate the electron lens action regions of the front electron lens (Lens 1) and the rear electron lens (Lens 2), the fourth grid G₄ is constituted to have its length l = (l₁ + l₂) larger than 1.5 times the aperture diameter of the third grid G₃ and accordingly the smaller aperture diameter D₁ of the fourth grid G₄; that is, l ≥ 1.5 D₁.

According to the arrangement so far described, the aberration amount of the rear accelerating electron lens (Lens 2) is improved, giving rise to more improvement of the whole aberration of the electron lens system.

FIG. 6 is a graph indicating compared results of the spherical aberration coefficient between the electron gun of this invention and a conventional electron gun. In this graph of FIG. 6, the ordinate indicates an amount g₃ relating to the spherical aberration coefficient, (which will be represented in the following equation of aberration coefficient) while the abscissa indicates a focal distance f₁ at the side of an object (cross-over point) side. In this graph, a curve I represents a case of an electron gun of ordinary unipotential type shown in FIG. 4 having the respective aperture diameter of the third grid G₃, the fourth grid G₄ and the fifth

grid G₅ the same and the length l of the fourth grid G, as 21.0 mm. A curve II represents a case of an electron gun of unipotential type shown in FIG. 5 in which the diameter D₂ of the rear electron lens (Lens 2) and the aperture diameter of the fifth grid G₅ is the same as that of the fourth grid G₄ at its side facing to the fifth grid G₅ and is selected larger than the diameter D₁ of the front electron lens (Lens 1), with D₁ = 13.8 mm, D₂ = 16.4 mm, l = 28.1 mm, l₂ = 10 mm. Curves IIIA, IIIB and IIIC represent cases of the electron gun of unipotential type shown in FIG. 3 according to this invention with l = 28.1 mm, 33.1 mm and 38.1 mm, respectively, where D₁ = 13.8 mm, D₂ = 16.4 mm, D₃ = 22.0 mm and l₂ = 10 mm are common.

The equation relating to the aberration coefficient will be represented with reference to FIG. 7. If the spherical aberration coefficient is taken as C_S, the magnification of lens as M, and a half-angle of maximum divergent angle of the electron beam from the cross-over point (object point) O as α_o, the aberration amount Δ_r (the radius of beam spot impinged on an image plane 1) is given as: Δ_r = MC_Sα_o³

$$C_S = C_{S0} + \frac{C_{S1}}{M} + \frac{C_{S2}}{M_4} + \frac{C_{S3}}{M_4} + \frac{C_{S4}}{M_4}$$

The amount g₃ in FIG. 6 indicates an amount expressed by:

$$g_3 = C_{S0}/2$$

$$\Delta_r = (L_a \alpha^3) g_3$$

where f₂ represents the focal distance of the image side and L represents the distance from the object point to the image plane.

As is clear from FIG. 6, the electron gun according to this invention can offer an aberration coefficient better than that of the conventional electron gun shown in FIG. 5, resulting in a reduction of the aberration coefficient in an amount of 15 to 20%. Moreover, our work reveals that the aberration amount was not substantially increased even when the fourth grid G₄ is inserted into the fifth grid G₅ in overlapped state.

A practical embodiment of this invention will now be described.

FIGS. 8 and 9 illustrate a practical embodiment of the electron gun according to this invention, which comprises a cathode K and a first grid G₁ to a fifth grid G₅, each arranged in turn along the common axis. In this example, especially the fifth grid G₅ with the aperture diameter D₃ and the third grid G₃ with the aperture diameter D₁ are formed into a unitary structure and the fourth grid G₄ is placed within the fifth grid G₅ formed into the unitary structure. In this case, in an elongated portion 2 extending from the long fifth grid G₅ with opposed windows 3 and connected with the third grid G₃, so that the elongated portion 2 substantially corresponds to a lead portion by which the fifth grid G₅ is electrically connected with the third grid G₃. The fourth grid G₄ with a small aperture portion of diameter D₁ and a large aperture portion of diameter D₂ is inserted into the long fifth grid G₅ at its large aperture diameter portion and facing to the third grid G₃ at its small aperture diameter portion at the window portions 3. The small aperture diameter portion of this fourth grid G₄ and the third grid G₃ constitute a front electron

lens system (lens 1), while the large aperture diameter portion of the fourth grid G₄ and the fifth grid G₅ constitute a rear electron lens system (lens 2). Under this state, the first grid G₁ to the fourth grid G₄ are held together by common insulation holding rods 4. In this case, especially the fourth grid G₄ is held at the window portions 3. Since at the forward end portion of the fifth grid G₅ there is provided a shield plate 5 for getter-shielding, a distance l₃ between the forward end of the fourth grid G₄ and the shield plate 5 is selected to be such a distance to prevent the electron lens from being formed between the fourth grid G₄ and the shield plates 5; for example, a distance satisfying $l_3/D_3 \geq 0.57$. The electron gun thus arranged is placed into a neck portion 6 of a cathode ray tube envelope. In this case, if the inner diameter of the neck portion 6 is taken as D₄, the aperture diameter D₃ of the fifth grid G₅ can be selected so as to satisfy $D_4 > D_3 > 0.65 D_4$.

In this way, according to the present invention, as shown in FIGS. 8 and 9, the fifth grid G₅, and the third grid G₃, are mechanically formed into a unitary body, the fifth grid G₅ is not held directly by the insulation holding rods 4, but held at the same time when the third grid G₃ is held by the insulation holding rods 4; and the fourth grid G₄ is held by the straight insulation holding rods 4 through the window portions 3 formed in the elongated portion 2 of the fifth grid G₅ at the same time when the third, second and first grids G₃, G₂ and G₁, are all held. Thus, the distance between the opposing insulation holding rods 4 at their outside surfaces can be made smaller than the aperture diameter D₃ of the fifth grid G₅ so that the aperture diameter D₃ of the fifth grid G₅ can be increased until it approximates the inner diameter D₄ of the tube neck portion 6, and further the spherical aberration of the main electron lens system can be reduced.

FIG. 10 shows another embodiment of this invention. In this embodiment, the third grid G₃, the fourth grid G₄ and the fifth grid G₅ are formed separate, and under the condition that the fourth grid G₄ is inserted at its 40 large aperture portion into the fifth grid G₅, the fourth grid G₄ and the fifth grid G₅ are mechanically connected by an annular ceramic insulation material 7 via solder material. Then, the first grid G₁ to the fourth grid G₄ are held together by the same insulation holding rods 4 and the third grid G₃ and the fifth grid G₅ are connected to each other by proper lead wires, not shown, a desired electron gun being thereby constructed.

According to the electron guns of the invention shown in FIGS. 8 to 10, since the fifth grid G₅ is mechanically coupled with the third grid G₃ or the fourth grid G₄ to comprise a unitary body, which is not held by and between the insulation holding rods 4, the aperture diameter D₃ of the fifth grid G₅ can be increased to 55 approximate the inner diameter D₄ of the neck portion 6. Thus in the rear electron lens system (Lens 2) the aperture diameter D₃ of the fifth grid G₅ can be made larger than the aperture diameter D₂ of the fourth grid G₄, and without increasing the inner diameter D₄ of the neck portion 6, the spherical aberration of the main electron lens system can be reduced.

FIG. 11 is a graph showing a relationship between a current amount (mA) and a mean diameter (mm) of a beam spot on the phosphor screen with respect to the 60

aforesaid electron gun of this invention and the conventional electron gun of unipotential type of FIG. 4. In this graph of FIG. 11, curve IV indicates the relationship of the conventional electron gun and curve V that of the present invention. As will be apparent from FIG. 11, according to this invention, the beam spot is significantly improved.

Furthermore, it is also possible that the rear electron lens (lens 2) is formed as an extended-field type lens with the inner diameter of the end electrode large. Such a modified electron gun can also reduce the spherical aberration.

As described above, the electron gun according to this invention can provide a more reduced, or improved, spherical aberration than the conventional electron gun. By selecting the electron lens aperture of its front electron lens system smaller than that of the rear electron lens system, each electron lens action region being separated, so that the electron gun of this invention is suitable for use with a color picture tube, a projector tube and so on. The above describes preferred embodiments of the invention, but it will be apparent that many modifications and variations can be effected by one skilled in the art without departing from the spirit or scope of the novel concepts of the invention, so that the scope of the invention should be determined by the appended claims only.

We claim as our invention:

1. A unipotential type electron gun comprising a main electron lens system having a first electron lens system and a second electron lens system of which the electron lens operative regions are separated from each other, said first system being formed of a third grid and a fourth grid, said second system being formed of said fourth grid and a fifth grid, the aperture diameter of said fifth grid being larger than that of said fourth grid, and the aperture diameter of said fourth grid facing said fifth grid being larger than that of said fourth grid facing said third grid, wherein said third grid and said fifth grid are mechanically and electrically united into an unitary structure, wherein at least one window portion is formed in said unitary structure, and wherein said fourth grid is arranged within said unitary structure and wherein said fourth grid is held by means of at least one insulating holder through said window portion, which holder also holds first, second and said third grids and a shield plate attached to the front end of said fifth grid and $l_3/D_3 \geq 0.57$ where D₃ is the diameter of the fifth grid and l₃ is the distance from said shield plate to the front edge of said fourth grid.

2. An electron gun according to claim 1, in which said fourth grid is held by means of opposing insulating holders.

3. An electron gun according to claim 1, in which said insulating holders are glass beads.

4. An electron gun according to claim 2 wherein said fifth grid is larger in diameter than the distance between said opposing insulating holders.

5. An electron gun according to claim 1 wherein said electron gun is mounted into the neck portion of a glass envelope which has an inside diameter D₄ and $D_4 > D_3 > 0.65 D_4$ where D₃ is the aperture diameter of said fifth grid.
